UNITED STATES PATENT OFFICE

146,309

DESIGN FOR A TOOTHBRUSH TIMER

Ralph R. Hitt, Weatherford, Tex.

Application April 5, 1946, Serial No. 128,308

Term of patent 7 years

(Cl. D42—7)

To all whom it may concern:

Be it known that I, Ralph R. Hitt, a citizen of the United States, residing at Weatherford, in the county of Parker and State of Texas, have invented a new, original, and ornamental Design for a Toothbrush Timer, of which the following is a specification, reference being had to the accompanying drawing, forming a part thereof.

Figure 1 is a front elevational view of a toothbrush timer, showing my new design;

Figure 2 is a side elevation; and

Figure 3 is a rear elevational view of a toothbrush timer, in an inverted position from that disclosed in Figure 1.

I claim:

The ornamental design for a toothbrush timer, as shown.

RALPH R. HITT.
